Primary Examiner — Angela J Lee(74) *Attorney, Agent, or Firm* — Kilpatrick Townsend & Stockton LLP(57) **CLAIM**

The ornamental design for a light fixture, as shown and described.

DESCRIPTION

FIG. 1 is a bottom perspective view of a light fixture. FIG. 2 is a bottom plan view of the light fixture of FIG. 1. FIG. 3 is a right side elevation view of the light fixture of FIG. 1, it being understood that the left side elevation view is identical to the right side elevation view; and, FIG. 4 is a front elevation view of the light fixture of FIG. 1, it being understood that the rear elevation view is identical to the front elevation view.

Portions or features of the light fixture not shown in the drawings form no part of the claimed design. The dot-dot-dash broken lines in the drawings are included for illustrating environmental structure and form no part of the claimed design. The even broken lines in the drawings form no part of the claimed design.
